United States Patent Office.

JOHN AUGUSTUS BALL, OF GRASS VALLEY, CALIFORNIA.

Letters Patent No. 96,866, dated November 16, 1869.

IMPROVED CHAIN-ELEVATOR AND BUCKET.

The Schedule referred to in these Letters Patent and making part of the same.

To all whom it may concern:

Be it known that I, JOHN AUGUSTUS BALL, of Grass Valley, in the county of Nevada, and State of California, have invented certain new and useful Improvements in Endless Chain-Elevators and Buckets; and I do hereby declare that the following is a full and exact description of the same, reference being had to the accompanying drawings, and to the letters of reference marked thereof.

The nature of my invention consists principally of a device for opening and closing the buckets at the proper time of filling and discharging their contents, which works automatically, by means of jointed arms, and the peculiar construction and attachment of the buckets to the endless chain or belts.

My device may be employed for elevating grain in store-houses, mud in dredging, sand in excavating, earth in ditching, and for other purposes when a self-charging and discharging-bucket is wanted.

Referring to drawings—

Figure 1 is a side elevation.

Figure 2 is a side elevation showing bucket passing around the lower drum.

Figure 3 is a side elevation of bucket.

Figure 4 is a back view of bucket.

The frame A is constructed at an inclination, and at each end are attached pulleys or drums B B'.

The lower drum, B', I construct larger in diameter than that of the upper one, so that the hinged gate of the bucket will not open when passing around its arc, and is provided with grooves C C' at each end.

The upper drum has also grooves, with projections a a', between which the links of the endless chains D enter as the machine is revolved.

A drum, E, which is also grooved, is attached to the under side of the frame, over which the chains and buckets pass in their revolutions. This drum may be raised or lowered to give a greater or less sweep to the bucket.

The buckets are attached bottom up to the endless chains by the transverse rods b b'.

From each end of the rods b' and c extend arms d d', that are bolted to the sides of the bucket, and these arms work on the pivoted joints as the machine is turned.

To the rear end of the bucket is hinged a flap or door, F, and when the contents are discharged, it falls by its gravity against the end of the bucket, and a guard, F', that is attached to the rod c and b' which rises automatically by the action of the jointed arms d d', and holds the door in place until it descends to the foot of the incline, when the jointed arms are expanded to allow the bucket to pass around the arc of the drum.

By this operation the door does not fly open, as the pitch is not sufficient to admit of it, and the door descends and holds it while it is being filled and carried to the top of the incline for discharging.

At that point the arms approach each other, drawing the guard and guard-rods that hold the door below it, which causes it to fly out, and the bucket discharges itself, and so on at each revolution.

In some cases the guards may be dispensed with, and the rods b and c be used alone, but I prefer to construct my machine with the guards, as set forth, to insure success in working.

Having thus described my invention,

What I claim, and desire to secure by Letters Patent is—

Operating elevator-buckets by means of the rods b b' c, and the jointed arms d d', which automatically raise and lower the guard and guard-rods at the proper point, in combination with the flap-door F, guard F', and said guard-rod c, the whole constructed and arranged substantially as described.

In witness whereof, I have hereunto set my hand and seal.

JOHN A. BALL. [L. S.]
